CHILD'S COMPARTMENTED FEEDING DISH

Jack J. Wendell, Burbank, Calif.

Application July 28, 1949, Serial No. 4,175

Term of patent 14 years

(Cl. D44—15)

To all whom it may concern:

Be it known that I, Jack J. Wendell, a citizen of the United States of America, and a resident of Burbank, county of Los Angeles, State of California, have invented a new, original, and ornamental Design for a Child's Compartmented Feeding Dish, of which the following is a specification, reference being had to the drawing as forming a part thereof.

In the drawing:

Fig. 1 is a side elevational view of a child's compartmented feeding dish showing my new design.

Fig. 2 is a top plan view; and,

Figs. 3 and 4 are respectively front and rear elevational views thereof.

I claim:

The ornamental design for a child's compartmented feeding dish, substantially as shown.

JACK J. WENDELL.
